PEN

Joseph V. Wuestman, Union, N. J., assignor to
George Ramsey and Frank J. Kent, New
York, N. Y.

Application November 18, 1931, Serial No.
575,787. Renewed September 2, 1933

13 Claims. (Cl. 120—42)

This invention relates to pens. It is particularly applicable to fountain pens, but certain features of the invention may be applied to other pens.

At present, it is necessary for fountain pen companies to manufacture and stock ten to fifteen types of pen points to meet the range of writing characteristics desired by different users. Some manufacturers advertise that they have so many different types of pens that the customer may select a "personal" pen particularly suited to his own hand writing. It is also necessary at present for some pen users to keep on hand at least two different pens, one for fine writing or ledger work, another for ordinary writing or for signatures.

The present practice makes it necessary for both manufacturers and dealers to carry a large stock of pens, thus tying up quite a large amount of money in stock on hand. The present practice also makes it necessary for the purchaser to try a number of pens before making his selection.

A general object of the present invention is to provide a writing pen which can be readily adjusted for different widths of ink line and different rates of ink flow.

Another object of the invention is to provide a writing pen having means to adjust the "set" of the nibs.

A further object of the invention is to provide a fountain pen in which the feed bar is held closely against the pen point.

Fig. 1 is a plan view of a fountain pen embodying a preferred form of the invention.

Fig. 2 is an enlarged plan view of the forward end of the pen shown in Fig. 1.

Fig. 3 is a greatly enlarged section taken on line 3—3 of Fig. 2.

Fig. 4 is a sectional exploded view corresponding to Fig. 3.

Fig. 5 is an exploded view corresponding to Fig. 2.

Fig. 6 is a detail plan view showing a modified form of the invention.

Fig. 7 is a detail longitudinal section showing a second modification of the invention.

Fig. 8 is a detail longitudinal section showing a third modification of the invention.

Reference will now be had to Figs. 1 to 5 inclusive. The pen designated as a whole by 1 has the usual barrel 2, which is adapted to contain a supply of ink. From the end of the barrel there projects a feed bar 4 and a pen point designated as a whole by 5. From the under side of the feed bar, there is inserted a tapered annular bushing 6,

which is interiorly threaded and preferably made of metal. A small screw 7, having a tapered head portion, passes through the pierce of the pen point and a portion of the feed bar and then engages the threaded bushing 6. By tightening 60 down the screw 7 pressure is applied tending to separate or vary the "set" of nibs 8, 8. By the "set" of the nibs is meant the tendency of the nibs to hug one another.

It will be apparent that the screw 7 may be adjusted to vary the set of the nibs over quite a wide range, whereby the flow of ink, and the width of the line which the pen will make, will be correspondingly varied. It is not necessary in all cases to adjust the screw 7 so that the tips 70 of the nibs will be separated when the pen is off the paper. By applying a pressure with screw 7 which merely tends to separate the nibs, the nibs will more readily separate when the point is applied to the paper. Hence, a wider line and 75 higher rate of ink flow will be obtained than when no pressure is applied by screw 7. The feed bar 4 is provided with two feed channels 9, 9 on opposite sides of the screw 7, and the two channels meet at 10. Thus the screw 7 does not 80 interfere with the flow of ink.

In the form of the invention shown in Fig. 6, the set of the nibs is varied by a small turnbuckle 15, the arms of which are welded, soldered, or otherwise secured to the nibs. With this form 85 of the invention, a double channeled feed bar (as in Fig. 5) may be used, but an ordinary single channel feed bar may likewise be used.

In the form of the invention shown in Fig. 7, an adjustment screw 11 operates in a manner 90 similar to the adjusted screw in the first form of the invention, but engages a block 12 suitably secured to the upper side of the feed bar as by molding the feed bar about it. Space is provided at 13 for ink flow beneath block 12.

In the form of the invention shown in Fig. 8, an adjustment screw 14 is operable from beneath the feed bar and has a conical end which engages the under side of the pierce of the pen. In this form of the invention, the pierce engaging end 100 of the adjustment screw is preferably enlarged to prevent removal; and the screw is assembled with respect to the feed bar before the feed bar and the pen point are assembled together. Preferably, the feed bar is of a double channeled type 105 similar to that shown in Fig. 6.

It is very desirable that the feed bar should be at all times in close contact with the pen point, because otherwise the film of ink will break, thus interfering with the flow. The ordinary prac- 110

tice in assembling pens is to heat the feed bar and bend it, so that it contacts with the pen point. This practice does not always produce satisfactory results. In the forms of the invention shown in Figs. 2 and 7, the adjustment screw, in addition to adjusting the set of the nibs, draws the pen point and the feed bar together, thus insuring contact at all times between the pen point and the feed bar.

10. It will be apparent that the present invention greatly simplifies the manufacture and sale of pens in that a stock of only three or four different pen points may be carried; and the purchaser may readily adjust the point to his own hand writing. Also, the user may readily adjust his pen for different types of work, thus making it unnecessary for him to purchase more than one pen.

20. The present invention may be embodied in forms other than those particularly disclosed and hence the foregoing disclosure is merely illustrative in compliance with the patent statutes and is not to be considered as limiting.

I claim:

25. 1. In a pen, a pen point having nibs, and adjustable means carried by the pen operative to exert on the nibs a force tending to separate them from one another.

30. 2. In a pen, a pen point having nibs, and adjustable wedging means operative to exert on the nibs a force tending to separate the same.

35. 3. In a pen, a pen point having nibs, a feed bar, and means exerting a force on the nibs tending to separate them from one another, said means also being operative to urge the pen point toward the feed bar.

40. 4. In a pen, a pen point having nibs and a pierce, and an adjustable screw having a tapered portion engaging the pierce to vary the set of the nibs.

45. 5. In a pen, a pen point having nibs and a pierce, a feed bar, said feed bar having a threaded aperture, and a screw passing through the pierce and engaging said threaded aperture, the screw having a tapered portion which engages the pierce to vary the set of the nibs.

6. In a pen, a pen point having nibs and a pierce, a feed bar, said feed bar having a threaded aperture, a screw passing through the pierce from above the same and engaging said threaded aperture, said screw having a tapered head which engages the pierce and operates to vary the set of the nibs and to urge the pen point toward the feed bar. 80

7. In a pen, a pen point having nibs, means secured to the nibs, and adjustable separating means cooperating with the first means and operative to exert on the nibs different magnitudes of force tending to separate them from one another. 85

8. In a pen, a pen point having nibs, and a turnbuckle secured to the point and operative to vary the set of the nibs. 90

9. In a pen, a pen point having nibs, a feed bar having two feed channels, and means passing between the channels and operative to exert on the nibs a force tending to separate the same. 95

10. In a quill type pen, a pen point having nibs, adjustment means secured to each nib and extending across said nibs and adjustable to act as a tension member to control the spread of the slit between the said nibs. 100

11. In a quill type pen, a pen point comprising nibs, adjustable means connected with each nib and comprising a tie member extending across said nibs and adjustable to restrain the separation of said nibs when writing pressure is applied to the point of the pen. 105

12. In a quill type pen, a pen point having nibs, an adjustable member connected with each nib and being adjustable to control the spread of said nibs relative to each other. 110

13. In a quill pen, a pen point having nibs, an adjustable member is secured to each nib and bridging the slit between said nibs and being adjustable to control the effective width of said slit during writing operations. 115
